US0D1098228S

(12) **United States Design Patent** (10) **Patent No.:** **US D1,098,228 S**
(45) **Date of Patent:** **** Oct. 14, 2025**

(54) **AUTOMOTIVE TRANSMISSION FORK**

(71) Applicant: **Calimer Transmissions LLC**,
Waynesboro, PA (US)

(72) Inventor: **Benjamin W. Calimer**, Waynesboro,
PA (US)

(73) Assignee: **Calimer Transmissions LLC**,
Waynesboro, PA (US)

(**) Term: **15 Years**

(21) Appl. No.: **30/002,027**

(22) Filed: **May 1, 2025**

Related U.S. Application Data

(62) Division of application No. 29/865,749, filed on Aug.
10, 2022, now abandoned.

(51) **LOC (15) Cl.** **15-01**

(52) **U.S. Cl.** ..... **USPC** **D15/5; D12/179**
